Application August 11, 1952, Serial No. 303,758

9 Claims. (Cl. 110—8)

This invention relates to an incinerator stoker or refuse burning furnace. Such furnaces are used to burn garbage and the like for municipalities. Substantially identical furnaces are used for industrial purposes for disposing of refuse such as boxes, crates, papers and the like.

The efficiency of such furnaces is determined by the quantity of material reduced to dry ash in a given time, and by their direct consumption of the odors of combustion. To obtain the consumption of the odors of combustion, the furnace must be maintained constantly in operation at a temperature that will consume all the gases given off by the combustion, and to accomplish this result, the furnace should not need opening for cleaning except at rare intervals of a week or more.

Also the furnace must break up masses of material that might form as clinkers and adhere to the furnace bed or sides, and which might have a sodden core, and the forward feeding grate bars of this invention successfully accomplish that purpose. It is found in practice that with the forward feeding, the material is progressively broken and spread over the whole grate bed, and burned, so that when it reaches the dump grate, only fine dry ash is left, when burning municipal refuse, plus of course a quantity of tin cans and other unburning materials which are cleared from the furnace by opening the dump grate, from which they fall to the ash pit below. Air is admitted to the burning bed from below. Because of the progressive burning, it has been found that more air passes through the lower end of the grate, where the combustion is more nearly complete, than through the upper end, where unconsumed material blocks the passage of air through the grate. As the air passes through the lower portion of the grate, it passes upwardly, toward the escape flue, nearly parallel with the grate, and in passing over the top of the burning material, as the material is periodically raised and forwarded by the upwardly lifting grate bars, the heated air enters the material from the top and hastens the drying and combustion and aids in consuming the escaping gases. Also, the heated air that passes through the grate further up the slope passes back to the escape flue, nearly parallel to the burning bed, and hastens the drying and the combustion there.

It has been found from installations of the instant invention that the quantity of material consumed is fifty percent more than that consumed in other refuse burning furnaces of similar size, also since the instant furnace need not be opened for the removal of ash, the furnace is not cooled and all gases of combustion are consumed, the ash is taken from the hoppers under the dump grates and the removal does not cool the furnace. Also this constant agitation, spreading, and maintenance of constant temperature eliminates the formation of clinkers. The maintenance of constant temperature also greatly reduces maintenance costs.

Also furnace stokers have had other drawbacks which have prevented their wide acceptance such as clogging or jamming in the operation of the stoker bars by the

2

presence of metal in the refuse. Also the strength of the bars has not been adequate in many cases to absorb the shock where heavy articles are dropped upon them.

The objects of the instant invention are those set forth above and to overcome these difficulties heretofore experienced and to make a furnace which can be readily adapted to either municipal or industrial use and which will consume refuse at a rapid rate, together with its gases, and will not break under heavy impact and will not jam with the presence of bolts and other foreign pieces of iron. Another object of the invention is to make the grate bars wide, to more readily move forward the wet soggy material and the large refuse. The formation of the stoker bars, either stationary or lifting, with a strut or portion projecting forwardly toward an adjacent lifting stoker bar, to nearly close the space between them, is also an important feature of the invention. Another object of the instant invention is to make the furnace in sections so that it may be extended to substantially indefinite size and for many varieties of installations without modification of manufacturing methods.

It has been found most desirable in the building of furnaces for the intended purposes to slope the grate surface downwardly forwardly from the bridgewall. This serves not only the purpose of introducing the refuse at the top of the sloping surface and near the bridgewall over which the most intense heat of the furnace passes to quickly dry out the incoming refuse, but as raw garbage and trash are fed to the furnace the moisture must be driven off before actual burning can take place. Thus this material must be introduced to the furnace at the point of highest temperature (the bridgewall end) where the incandescent gases pass over it and dry it out in the shortest possible time. As the material dries and ignites it is moved forward down the grates. Also this downward forwardly sloping structure permits ready attention to the lower portion of the grate should any substances be caught therein which require removal from the top surface of the grate structure, and most important of all, it greatly facilitates the combustion of both refuse and gases, as above described. In the preferred form the consumed refuse is removed from the furnace through means of a dump grate at the front end which drops the ashes into a pit from which they may be removed by passing a truck thereunder.

The above and other objects and advantages of the invention will be apparent from the following description and the accompanying drawings forming a part hereof and in which:

50 Figure 1 is a diagrammatic longitudinal sectional view through the furnace.

Figure 2 is a side elevational view showing the grate structure in some detail.

55 Figure 3 is a continuation of Figure 2 to the right.

Figure 4 is a longitudinal sectional view showing the intermediate supporting members for supporting the grate bars at their center.

Figure 5 is a continuation of Figure 4 to the right.

60 Figure 6 is a plan view of the upper end of the grate surface.

Figure 7 is a side elevation of one bearing bar section.

Figure 8 is a top plan view of a portion thereof.

65 Figure 9 is sectional view on line 9—9 of Figure 7.

Figure 10 is a front sectional view of a rocking grate bar.

Figure 11 is an end elevational view thereof.

70 Figure 12 is a fragmentary view showing the attachment of the stoker bar arm to the end of a rocking grate bar.

Figure 13 is a sectional view showing the attachment of a stoker bar arm intermediate the ends of the bar,

Figure 14 is a sectional view on line 14—14 of Figure 10.

Figure 15 is a top plan view of a stationary grate bar.

Figure 16 is a front elevational view thereof.

Figure 17 is an end elevational view thereof.

Figure 18 is a transverse sectional view thereof.

Figure 19 is a transverse sectional view of a rocking grate bar and an adjacent stationary bar with a foreign piece of iron between them.

In the drawings similar numerals refer to similar parts throughout the several views. The furnace 1 has a front wall 2 and a rear or bridgewall 3 with an escape flue 4 over the bridgewall. The grate 5 slopes downwardly forwardly between the walls. Air is admitted beneath the grate through draft opening 6. The grate bars 7 are mounted on horizontal trunnions 8 in sockets 9 in sectional bearing bars 10 which are bolted together as shown at 11 and bolted to I-beams 12 as shown at 13. These I-beams are supported adjacent their forward end in supporting beams 14 and bolted thereto, which in turn is connected with the front wall 2 of the furnace and at their rear ends the beams are supported on bearing bar beam anchors 15 on which the beams are allowed to slide in case of expansion or contraction in their heating and cooling.

The sectioned bearing bars 10 are preferably made up in three types, one being a forward bearing bar 16 and a rear bar 17 with intermediate bars 18. If a longer furnace grate is desired, additional intermediate sections 18 may be interposed on longer I-beams. The group of bearing bars extending the whole width of the furnace are connected together by tie rods 19 at their upper ends and by beam 14 at their lower ends. Each bearing bar has therein a plurality of sockets 9 which are elongated in the direction of the length of the bar, and at the lower end of the sockets they each have rearwardly projecting guards 20 to retain the trunnions 8 of the grate bars within their sockets. At the upper end of the sockets are placed forwardly projecting trunnion guards 21 which are held in place by bolts 22 as clearly shown in Figure 7. The opening at the top of the sockets 9 is less than the diameter of the trunnions 8.

The grate bars 7 may either be of the rocking kind 23 or the stationary kind 23'. The rocking bars as well as the stationary bars have the trunnions 8 at their ends resting in the elongated sockets 9. The rocking grate bars have rear curved shields 24 projecting from their rear edge and fitting reasonably closely to the forward edges 25 of the next upper bar, whether that bar be rocking or stationary. The curved shields 24 prevent the material from sliding through the space between the bars and the forward edge 25 of the adjacent bar extends between the trunnions and projects forwardly as shown in Figure 19 to make as close a connection with the next forward bar as possible and yet avoid interference with the operation of the rocking bars. Immediately beneath this holding edge 25, the bar sharply recedes, to allow material to work through, between that bar and the next forward bar. These bars expand considerably in use with high temperatures and it is most important to maintain them in operative relationship so that the material on them may be moved forwardly as it is consumed.

For the burning of industrial refuse it has been found that alternately placed stationary and rocking grate bars operate best, the stationary bars allowing closer and more accurate spacing with their adjacent rocking bars, to make the catching of foreign iron between the bars less likely. Both stationary and rocking grate bars have their trunnions in the elongated sockets 9, however, and the forward bar is pushed forwardly by foreign iron pieces 26, as shown in Figure 19, until they work through and the operation of the bars is not interrupted.

The stationary bars have inset bearing surfaces 27 in their rear lower edges and on these surfaces the bars may move transversely on stops 28 which are in the form of

pins placed in suitable openings in the sectioned bearing bars, the stops being clearly shown in Figure 7.

In most of the views, the rocking grate bars are shown as alternately spaced with stationary grate bars, and this 5 is the preferred form for the industrial refuse furnace, as above stated. However, for burning municipal garbage, it has been found preferable to have the whole grate surface composed of rocking grate bars, and the section of the grate shown in Figure 6 is of this kind. Both the bearing bars and rocking grate bars are identical in both 10 constructions. The bearing bars are only modified when certain stationary bars are used by the insertion of the stops 28 to hold up their back edges.

The rocking grate bars are grouped in alternate units, 15 one unit being connected by connecting bar 29 and the other by connecting bar 30. These connecting bars are connected to power cylinders 31 and 32 respectively by push rods 33, and they are operated alternately by lever 34. The cylinders operating these rocking grate bars 20 may be so operated as to slope the rear top edge of the bars near to the axis of the next rear bar trunnion, that is, they will slope backwardly downwardly slightly from parallelism with the bearing bars, so iron pieces on top of a rear bar will roll forwardly and fall on the top rear 25 edge of the next lower bar, rather than falling between the bars, thus this foreign iron will roll down to the dump grates.

The power cylinders and their pistons are so related 30 in their construction and operation as to bring the rocking grate bars in line with the grate and hold them there, when the bars are lowered, except as just described. No additional stops are required. The connecting bars 29 and 30 may be connected to the rocking bars 7 at 35 their ends as shown in Figure 11 where the yoked curved casting 35 is bolted to the ends of the rocking bar at 36. So that the thrust on the push rods may be straight it is often preferred to attach these rods intermediate the ends of the rocking bars and this is accomplished by 40 means of the yoked member 37 which has bearing surfaces 38 and 39 bearing upon adjacent portions of the rocking bar and it is held in place by bolt 40 passing through opening 41 in the bar. Also on the face of the shield of the bar are seats 42 to hold the forward edge of this member 37 firmly in place. As shown in Figure 10 these openings 41 and seats 42 are variously placed 45 across the rocking bar to allow considerable selection for the location of the bar arm 37.

As clearly shown especially in Figures 6 and 15, both 50 the rocking and stationary grate bars have large air openings 43 therein to assure adequate air for efficient combustion of the refuse.

These furnaces are so large and are adapted to take 55 crates and boxes of such large dimensions that frequently very heavy material is dropped upon the grates, sometimes even logs of wood falling upon them. Their heavy impact would be so great as to injure grates supported only at their ends and it is therefore one of the objects of this invention to support the grates, both rocking and stationary, intermediate their ends and the central bearing bar 44 is shown in Figure 4 as being mounted on one I-beam 12 and the bearing bar 44 has plurality of upwardly projecting sockets 45 which receive arcs 46 and 60 47 on the stationary and rocking grate bars respectively. It will be observed that when either of these grate bars are moved forwardly by the presence of iron particles therebetween, that they will be raised up and the sockets for the end trunnions of these bars are slightly larger than is otherwise required to allow for this additional elevation.

At the forward end of the grate is placed the dump 65 grate 48. This grate is pivoted at 49 and it comprises a plurality of horizontal sections connected together having a pintle 50 underneath and these sections are lowered as a group by the toggle lever 54 connected to the pintle, 70 and which is operated by the piston 51 in power cylin-

der 52 by turning hand lever 53. The toggle lever 54 and the position of the piston in the power cylinder 52 are so related as to keep the dump grates horizontal when the piston is forward. Between sections of the dump grate 48 are dead plates 48' held up by supports 55. These dead plates are grate sections extending above the push rods 33.

At the upper end of the grate there is an expansion grate 56 with trunnions 57 fitting in sockets 9 at the top of the end bearing bar 17 and center bearing bar 44. These bearing bars have brackets 58 to hold the expansion grates up, at an angle to the bearing bars. This expansion grate rests at its rear end against the bridge-walls of the furnace and it slides vertically thereon with the expansion and contraction of the grate. As shown at 59 the forward end of this expansion grate extends downwardly on the trunnions, close to the rear end of the adjacent rocking grate bar, so that when the refuse is dropped through the opening 60 onto the upper end of the grate, metallic particles will roll from this expansion grate onto the adjacent rocking grate bar. In spite of this precaution, however, should metallic particles get between the rocking grate bar and the expansion grate, the expansion grate may move upwardly in its extended sockets 9 and thereby leave the rocking grate bar operative.

Refuse is fed to the furnace chamber through opening 60, near the top of the grate, this being the hottest part of the furnace, and it is partially dried by passing through the hot gases as they pass out over the top of furnace bridgewall 3, through escape flue 4. As the drying and burning refuse is moved down by the rocking grate bars it reaches the dump grates 48, from which it is discharged to pit 61. The expansion grates 56 also prevent the undue escape of air between the ends of the grate and the furnace bridgewall 3.

What is claimed as new and is desired to be secured by Letters Patent is:

1. A furnace combustion chamber for burning refuse having a front wall and a bridgewall and an escape flue over the bridgewall, a grate sloping angularly downwardly from adjacent the top of the bridgewall toward the front wall, the grate having grate bars therein pivoted horizontally at their forward edges adapted to be upwardly tilted at their rear edges to feed burning refuse forwardly, the furnace chamber having an opening in its top over the grate and adjacent the bridgewall, through which refuse is dropped to the grate near its upper end and adjacent the escape flue, the refuse adapted to be progressively spread and burned by upwardly tilting the grate bars, means to admit air under the grate, the air passing through the grate and across the top of the grate to the escape flue, to facilitate the burning of the refuse on the grate, its drying when turned up by the grate bars and the consumption of gases escaping from the refuse.

2. A furnace combustion chamber for burning refuse having a front wall and a bridgewall and an escape flue over the bridgewall, a grate sloping angularly downwardly from adjacent the top of the bridgewall toward the front wall, the grate having grate bars therein pivoted horizontally at their forward edges adapted to be upwardly tilted at their rear edges to feed burning refuse forwardly, means to slidably support the grate on the bridgewall to allow for its expansion and contraction, means between the juncture of the grate and bridgewall to prevent the passage of material therebetween, the furnace chamber having an opening in its top over the grate and adjacent the bridgewall above said means between the juncture of the grate and bridgewall, through which refuse is dropped to the grate near its upper end and adjacent the escape flue, the refuse adapted to be progressively spread and burned by upwardly tilting the grate bars, means to admit air under the grate, the air passing through the grate and across the top of the grate to the escape flue, to facilitate the burning of the refuse

on the grate, its drying when turned up by the grate bars and the consumption of gases escaping from the refuse.

3. A furnace combustion chamber for burning refuse having a front wall and a bridgewall and an escape flue over the bridgewall, a grate sloping angularly downwardly from adjacent the top of the bridgewall toward the front wall, the grate having grate bars therein pivoted horizontally at their forward edges adapted to be upwardly tilted at their rear edges to feed burning refuse forwardly, means to slidably support the grate on the bridgewall to allow for its expansion and contraction, hinged means covering the juncture of the grate and bridgewall and extending adjacent the rear edge of the next adjacent upwardly rocking grate bar to prevent the passage of material between the grate and bridgewall and between the hinged means and the adjacent grate bar, the furnace chamber having an opening in its top over the grate and adjacent the bridgewall above said hinged means, through which refuse is dropped to the grate near its upper end and adjacent the escape flue.

4. A furnace combustion chamber for burning refuse having a front wall and a bridgewall and an escape flue over the bridgewall, a grate sloping angularly downwardly from adjacent the top of the bridgewall toward the front wall, the grate having grate bars therein pivoted horizontally at their forward edges adapted to be upwardly tilted at their rear edges to feed burning refuse forwardly, the grate having partially closed supporting sockets at the ends of the grate bars, and trunnions on the bars rotating in said sockets, intermediate supports for said grate bars consisting of standards projecting upwardly toward the bars intermediate their ends and having on their respective tops open sockets extending transversely of the bars and arcs on the bottoms of the bars riding in said sockets upon the tilting of the bars, to support them between their ends, the furnace chamber having an opening in its top over the grate and adjacent the bridgewall, through which refuse is dropped to the grate intermediate the grate bar ends and near the grate upper end and adjacent the escape flue.

5. A furnace combustion chamber for burning refuse having a front wall and a bridgewall and an escape flue over the bridgewall, a grate sloping angularly downwardly from adjacent the top of the bridgewall toward the front wall, the grate having grate bars therein pivoted horizontally at their forward edges adapted to be upwardly tilted at their rear edges to feed burning refuse forwardly, each bar having a curved guard at its upwardly turning rear edge to prevent material from falling between the bars, a dump grate between the lower end of the sloping grate and front wall, said dump grate being horizontally pivoted at its forward edge, and means to open the same to clear the grate surface, the furnace chamber having an opening in its top over the grate and adjacent the bridgewall, through which refuse is dropped to the grate near its upper end and adjacent the escape flue.

6. A furnace for burning refuse comprising a downwardly sloping forwardly feeding grate adapted to receive refuse at its top and to pass it forwardly and downwardly in burning, bearing bars for said grate having bearing sockets opening transversely thereof, said sockets being elongated longitudinally of the bearing bars, the grate comprising a plurality of bars, trunnions extending horizontally from the ends of the grate bars and on which the rear edges of the grate bars are tilted upwardly and forwardly, the rear edges having downwardly projecting curved material blocking shields thereon, the trunnions riding in said bearing sockets and due to the slope of the grate, tending to rest in the lower ends thereof, the grate bars being adapted to slide up on their trunnions, the trunnions sliding upwardly in the elongated sockets, when an object is caught between the bar lower edge and the adjacent grate structure, whereby the grate bars may continue to be raised and lowered without binding the bearing bars having projections directed centrally of and

across the top of each socket to retain the trunnions therein at both extreme positions of their movement.

7. A furnace for burning refuse comprising a downwardly sloping forwardly feeding grate adapted to receive refuse at its top and to pass it forwardly and downwardly in burning, bearing bars for said grate, the grate comprising a plurality of spaced upwardly tilting material forwarding grate bars with curved downwardly extending material blocking shields on their rear edges, and trunnions extending horizontally from their ends adjacent their front edges, the bearing bars having sockets to receive said trunnions and spaced alternately with said bars, continuous material supporting bars likewise having trunnions extending horizontally from their ends, means on the bearing bars to support the forward edges of the continuous supporting bars parallel with the bearing bars, the bearing bars having bearing sockets opening transversely thereof, said sockets being elongated longitudinally of the bearing bars, for both said tilting and continuous supporting bar trunnions, said last named trunnions due to the slope of the grate, tending to rest in the lower ends of their sockets, and being adapted to slide upwardly therein when an object is caught between the forward edge of the continuous supporting bars and the adjacent bar shield, whereby the upward tilting grate bars may continue to be raised and lowered without binding the bearing bars having projections directed centrally of and across the top of each socket to retain the trunnions therein at both extreme positions of their movement.

8. A furnace for burning refuse comprising a downwardly sloping forwardly feeding grate adapted to receive refuse at its top and to pass it forwardly and downwardly in burning, forwardly and downwardly sloping spaced beams extending for the length of the furnace and supported therein at each end, longitudinally sectioned bearing bars on said beams, said bars being connected together and to said beams, each bearing bar having a plurality of elongated sockets therein, a plurality of grate bars having trunnions extending horizontally from their ends and adapted to rest in the lower ends

of sockets of aligned pairs of said bearing bars, and to be moved upwardly therein upon receiving pressure at their lower edges the bearing bars having projections directed centrally of and across the top of each socket to retain the trunnions therein at both extreme positions of their movement.

9. A furnace for burning refuse comprising a downwardly sloping forwardly feeding grate adapted to receive refuse at its top and to pass it forwardly and downwardly in burning, bearing bars for said grate, the grate comprising a plurality of spaced upwardly tilting material forwarding grate bars extending a substantial distance across the width of the furnace with curved downwardly extending material blocking shields on their ends adjacent their rear edges, and trunnions extending horizontally from their front edges, the grate bars being spaced from each other, and each bar having a top portion having multiple rectangular openings therein extending between their front and rear edges, the front edge being straight and in line with the forward edge of the trunnions and projecting forwardly in close juxtaposition to its next lower bar, and the portion of the bar between the trunnions and beneath said top portion, immediately beneath its foremost extension sharply receding to provide a space 20 to allow material to pass between said bar and its next forward bar after it has once fallen past said top portion.
